APPARATUS FOR ERECTING COLUMNS ON STEEL STRUCTURES

Filed Sept. 20, 1928

Inventor
William H. Lotts
George C. Mueller Atty

UNITED STATES PATENT OFFICE

WILLIAM H. LOTTS, OF RIVER FOREST, ILLINOIS, ASSIGNOR TO THE OVERLAND CONSTRUCTION COMPANY, OF CHICAGO, ILLINOIS, A CORPORATION OF ILLINOIS

APPARATUS FOR ERECTING COLUMNS ON STEEL STRUCTURES

Application filed September 20, 1928. Serial No. 307,122.

My invention relates to an improved apparatus for erecting columns on steel structures.

According to present methods when a steel column is being erected in a building structure it is secured by a sling made of cable or occasionally of chain or heavy rope, and then raised by a derrick and placed in position. This system leaves very much to be desired from the standpoint of economy and safety. As far as economy is concerned a great deal of unnecessary time is consumed in placing the column after it is raised, as it does not necessarily stand in the position in which it is to be used, generally inclining at an angle from the vertical. In addition the cable or whatever is employed to encircle the column and grip it according to the present system is apt to be cut or broken, or slippages can easily occur, any of which are apt to cause very serious accidents.

Accordingly the principal object of my invention is the provision of an improved method of and means for erecting steel columns.

Another object is the provision of an improved sling structure.

Another object is to raise a column with a high degree of safety.

Another object is to raise a column in the position which it will assume when riveted into place in the steel structure.

Other objects and features of the invention will be apparent from a consideration of the following detailed description taken with the accompanying drawings wherein

Fig. 1 is a perspective view of the top of a column showing my improved sling as applied thereto;

Fig. 2 is a fragmentary front elevational view, and

Fig. 3 is a side view of one of the anchor blocks in position over the top of a column.

Before proceeding to a description of the method of employing my invention I shall refer to a preferred form of apparatus with which the method is practiced. I refer to this apparatus as a "sling" because it takes the place of the usual sling employed in steel construction. It is not meant therefore to

limit the invention in any way by the use of this term.

The purpose of the apparatus is to grip a steel column 10 employed in steel construction work and which has a pair of splice plates 11 secured at both sides thereof by rivets 12. In erecting the column, that is placing and then riveting it into position the splice plates 11 extend upwardly, the lower portion of the column (not shown) being secured to the top of a previously placed column of the same general character.

The sling includes as its main parts anchor blocks 13, anchor bar 14 and an equalizing cable 16. These parts are assembled in the manner shown in Fig. 1 for raising the column in a vertical position. In order that those skilled in the art may understand fully all of the details of the invention I shall point out all of the features connected with these main parts.

The blocks 13 are of course the same and one of them will be described as exemplifying the construction of both. The block is split at 13^a to provide a pair of legs which extend on opposite sides of the splice plate. Each of these legs is provided with an aperture 13^b which is vertically elongated to prevent the anchor bar from becoming bound when the blocks are lowered after the column has been placed. To absolutely prevent any possibility of binding, the top of the split portion 13^a is arranged as shown particularly in Fig. 3 to engage the top of the splice plate and so hold the anchor block so that the bar 14 will be at approximately the center of the aperture 13^b so that it can be readily extracted. The top of the block, that is the unsplit portion is provided with an aperture 13^c for receiving the equalizing cable.

The bar 14 extends preferably through the top central portion of the splice plate. A special aperture is provided in the splice plates for this purpose. This aperture is preferably in the center of the splice plate so that the column will land directly vertical to facilitate placing it, but an aperture in an offset position may be employed if it is desired to use my invention solely from the standpoint of safety without reference

to the ease with which the columns can be mounted into position. A link 17 is provided at one end of the bar 14 and a cable 18 is connected from this link to the equalizing cable 16 so that any possibility of the bar becoming detached from the rest of the sling is avoided. A second cable or ordinary manila rope as I have used successfully is also fastened to the link 17 for withdrawing the bar from engagement with the blocks 5 and splice plates making it unnecessary for a workman to climb to the top of the column. These two cables 18 and 19 function well together because with this arrangement the bar 14 may be withdrawn without possibility 10 of danger to workmen or others in the vicinity of the construction work.

The equalizing cable 16 is provided with loops at its ends extended through the apertures 13^c and there confined by clamps 21 of any suitable character. Another clamp 22 binds the cable together near the center to provide a loop 23 for receiving a derrick hook or the like.

When using the sling of my invention the splice plates are provided with one extra aperture at the ends for receiving the anchor bar 14. The splice plates are riveted to the columns as is the present practice, but the extra or mounting apertures are in the projecting ends. When a column is to be raised into its position in the structure of the building the anchor blocks 13 are extended over the ends of the splice plates and the bar 14 inserted. As a precautionary measure separate means may be employed for holding the bar in this position but I find that the ordinary pressure on the bar resulting from the weight of the column is adequate to hold it 30 in place with safety. A derrick hook is then secured in the loop 23 of the cable and the column lifted to the position in which it is to be placed.

When the column is in an elevated position 45 it is lowered directly into the position in which it is to be used without the necessity of guide-ropes or other means to hold it upright when placing it as it will hang directly vertically from its sling. When it is lowered to the place it is to occupy with its bottom end extending between two up-standing splice plates, temporary fastening means are used to hold it, such as a couple of drift pins or the like. The sling is then 55 removed by withdrawing the bar 14 and the column is then riveted into position in the usual manner. When withdrawing the bar 14 it is simply necessary to lower the sling until the column rests in the position it is 60 to occupy. The filler in the block as already described makes it impossible for the bar 14 to bind in any way.

The legs of the anchor block fit quite snugly against the sides of the splice plate 65 so there is very little possibility of the bar

14 becoming bent through the weight applied to it. The strain which it encounters is practically a direct shearing stress and this can be figured very easily, as the relationship of load and shearing is well understood.

70

Although I have described several detailed features of my invention to enable those skilled in the art to practice the same I do not necessarily restrict myself to all of the 75 details shown, the invention being limited only by the scope of the appended claims.

What I claim as new and desire to protect by Letters Patent of the United States is:

80

1. An improved sling for securing steel columns for raising, said sling adapted to be used with splice plates secured to the top of a column, and comprising means extending over the ends of the splice plates, an anchor pin extending through said means and through apertures in the splice plates to secure said means to said splice plates, and means connected to both of said first mentioned means adapted to be gripped for raising the column directly vertically.

85

2. An improved sling for use in raising steel columns by engagement with the splice plates at one end thereof, said sling comprising anchor blocks extending over the ends of the splice plates, an anchor bar extending through apertures in the anchor blocks and splice plates, and a cable secured to both anchor blocks.

90

3. The combination defined in claim 2 100 wherein centrally disposed apertures are provided in the splice plates so as to cause the column to hang directly vertically when suspended by said cable.

95

4. An improved sling for use in raising steel columns by engagement with the splice plates at one end thereof, said sling comprising anchor blocks extending over the ends of the splice plates, an anchor bar extending through apertures in the anchor blocks and splice plates, a cable secured to both anchor blocks, the apertures in the anchor blocks being elongated vertically to facilitate insertion and removal of the anchor bar.

110

5. An improved sling for use in raising steel columns by engagement with the splice plates at one end thereof, said sling comprising anchor blocks extending over the ends of the splice plates, an anchor bar extending through apertures in the anchor blocks and splice plates, a cable secured to both anchor blocks, and a link at one end of the anchor bar for facilitating attaching a cable thereto for the removal of the anchor bar when out of arms reach.

115

6. An improved sling for use in raising steel columns by engagement with the splice plates at one end thereof, said sling comprising a pair of anchor blocks split ver-

120

tically throughout part of their length for engagement over the ends of the splice plate and having apertures therethrough above the split portion thereof, an anchor bar extending through apertures in the split portion of the blocks and the central upper portion of the splice bars, and a cable having its ends looped through the first mentioned apertures in said anchor blocks.

10 7. An improved sling for use in raising steel columns by engagement with the splice plates at one end thereof, said sling comprising a pair of anchor blocks split vertically throughout part of their length for engagement over the ends of the splice plate and having apertures therethrough above the split portion thereof, an anchor bar extending through apertures in the split portion of the blocks and the central upper 15 portion of the splice bars, a cable having its ends looped through the first mentioned apertures in said anchor blocks, means secured to the cable and anchor bar for attaching the anchor bar to the cable, and a 20 cable secured to the anchor bar for removing it from engagement with the anchor blocks and splice plates when out of reach 25 of an operator.

8. An improved sling for use in raising 30 steel columns by engagement with the splice plates at one end thereof, said sling comprising anchor blocks extending over the ends of the splice plates, an anchor bar extending through apertures in the anchor 35 blocks and splice plates, and a cable secured to both anchor blocks, the anchor bar apertures in the block being vertically elongated and so disposed with respect to the unsplit portion of the block that said portion may 40 rest on top of the splice plate when the column is placed without binding the anchor bar against the top of said elongated aperture.

9. A block for fitting over the end of a 45 splice plate for use with a sling of the character described, said block having legs extending on both sides of the splice plate, a vertically elongated slot in each leg for receiving a fastening bar, and a stop on the 50 block and adapted to engage the splice plate when the column is placed to prevent binding the fastening bar against the top of said elongated slots.

10. The block described in claim 9 where- 55 in said legs fit snugly against the sides of the splice plate and the load applied to the bar will be of a nature to shear the pin without bending it.

In witness whereof, I hereunto subscribe
60 my name this 15th day of August, 1928.

WILLIAM H. LOTT.
